UNITED STATES PATENT OFFICE.

JAMES HAND, OF PHILADELPHIA, PENNSYLVANIA, ASSIGNOR TO WILLIAM M. AYRES & SONS, OF SAME PLACE.

HORSE-BLANKET.

SPECIFICATION forming part of Letters Patent No. 542,931, dated July 16, 1895.

Application filed May 27, 1895. Serial No. 560,809. (No model.)

To all whom it may concern:

Be it known that I, JAMES HAND, a citizen of the United States, residing in Philadelphia, Pennsylvania, have invented certain Improvements in Horse-Blankets, of which the following is a specification.

My invention consists of certain improvements in the horse-blanket for which I filed application for Letters Patent on the 16th day 10 of July, 1894, Serial No. 517,708.

The horse-blanket forming the subject of said application was centrally split or divided at the front edge, so as to permit the neck-opening to be expanded or contracted to suit 15 horses of different sizes, the split or divided portion of the blanket being provided with an under flap, so as to provide a proper bearing for the blanket on the top of the neck and prevent exposure at this point when the split 20 or divided portion of the blanket was separated. This flap was firmly secured along one edge to the main portion of the blanket and its opposite edge was connected to the blanket through the medium of an elastic 25 strap or band; and the object of my present invention is to provide a more acceptable means than that formerly adopted for retaining the under flap in its proper position in respect to the blanket. This object I attain in 30 the manner hereinafter set forth, reference being had to the accompanying drawings, in which—

Figure 1 is a perspective view of sufficient 35 of the front portion of a horse-blanket to illustrate my present invention, and Figs. 2 and 3 are enlarged views of that portion of the blanket to which the invention particularly relates, Fig. 2 showing the blanket fully contracted, and Fig. 3 showing the blanket expanded 40 by spreading the divided back portion of the same.

In Fig. 1 A represents the body of the 45 blanket, and a the central slit or division formed in the front portion of the same above the neck, so as to permit the neck-opening of the blanket to be expanded or contracted, a strap b and buckle b' serving to permit expansion of the blanket to any desired extent.

B is the under flap, which is secured to the 50 blanket at a point adjacent to the inner end of the slit, but has free edges. From each edge of the under flap B, near the front end of the same, extends a strap d, which passes through an opening d' in the blanket and en-

gages a buckle d'', secured upon the outer 55 side of the blanket adjacent to said opening. These straps d therefore serve at all times to secure the opposite edges of the flap B in their proper position in respect to the opposite sides of the blanket, said straps d being 60 tightened when the strap b is tightened to draw the opposite halves of the blanket together, as shown in Fig. 2, and the straps d being correspondingly slackened when the strap b is slackened to permit expansion of 65 the neck portion of the blanket, as shown in Fig. 3.

The strap and buckle may, if desired, be used only in connection with one edge of the under flap B, the other edge being secured to 70 the corresponding side portion of the blanket; but the use of the adjustable straps in connection with each edge of the under flap is preferred.

Having thus described my invention, I 75 claim and desire to secure by Letters Patent—

1. The combination of a horse blanket having at the neck end a slit or divided portion provided with means for adjusting the same, 80 the under flap for closing the gap formed by said slit or divided portion of the blanket, means for securing one edge of said flap to the blanket and a strap connected to the other edge portion of said flap near the front end 85 of the same, said strap passing through an opening in the side of the blanket and being adjustably secured upon the outer face of the same, substantially as specified.

2. The combination of a horse blanket having at the neck end a slit or divided portion with means for adjusting the same, an under flap covering the gap formed by said slit or divided portion of the blanket, and straps extending from each edge portion of said flap 90 near the front end of the same through openings in the blanket on opposite sides of the slit or divided portion of the same, each of these straps being provided with adjustable 95 securing means on the outer side of the 100 blanket, substantially as specified.

In testimony whereof I have signed my name to this specification in the presence of two subscribing witnesses.

JAMES HAND.
